UNITED STATES PATENT OFFICE.

BERNIS M. SHIPLEY, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Original application filed March 11, 1921, Serial No. 451,508. Divided and this application filed July 9, 1923. Serial No. 650,390.

This invention relates to cash registers, and more particularly to indicating mechanism therefor.

The subject matter of this application constitutes a division of a copending application, Serial No. 451,508, filed on March 11, 1921, by B. M. Shipley.

The principal object of this invention is to provide a machine of a well known type with mechanism for disabling its indicating mechanism to prevent a display of totals or sub-totals.

The specific object of this invention is to render such disabling mechanism effective as an incident to the setting of a control lever preparatory to total and sub-total printing operations.

With these and incidental objects in view, the invention consists of certain novel features of construction and combinations of parts, the essential elements of which are set forth in appended claims and a preferred form of embodiment of which is hereinafter described with reference to the drawings which accompany and form part of this specification.

Fig. 1 is a sectional view through a machine to which the invention is shown applied.

Fig. 2 is a detail side elevation of a portion of the indicating mechanism and the means for disabling said indicators on total and sub-total printing operations.

Fig. 3 is a fragmentary view of the indicator carrying plate aliner.

Fig. 4 is a detail view having parts broken away showing the two alining devices for the indicating mechanism.

Fig. 5 is a detail view of the indicator aliner operating mechanism.

Fig. 6 is a detail view of the total lever showing mechanism for operating the disabling means.

Fig. 7 is a detail view showing the connection between the differential mechanism and the type wheel.

General description.

In cash registers or like machines having indicators such as shown herein, it is not desirable to have the totals or sub-totals on the various totalizers appear on the indicators when these totalizers are read or reset.

Mechanism is therefore provided herein for disabling the indicating mechanism on total and sub-total printing operations.

Cash register mechanism.

The machine to which the invention is shown applied is of the general type shown and described in Letters Patent of the United States No. 1,230,864, issued to W. A. Chryst on June 26, 1917; Letters Patent of the United States, Nos. 1,242,170 and 1,394,256, issued to F. L. Fuller on Oct. 9, 1917 and Oct. 18, 1921, respectively. It is to be understood however that this invention is applicable to many other types of machines, and it is therefore not desired to limit its use to the machine shown herein.

In view of the fact that a very complete description of the machine is given in the before-mentioned patents, only a very brief description thereof will be included herein. The keyboard comprises a plurality of banks of depressible keys 25 for setting up the amounts to be entered and for controlling the selection and engagement of the totalizers 26. An amount bank and differential mechanism are shown in Fig. 1. These keys when depressed are adapted to cooperate with a bell crank 27 carried by a totalizer actuating member 28. A latch member 24 supported on said bell crank normally connects the actuating member 28 to a driving segment 29. This segment is given an invariable extent of movement on every operation of the machine by means of a pair of cams 45 carried by the main drive shaft 46, a Y-shaped member 47 and a link 48, all of which are well known in the art. When the segment 29 is given this invariable movement the actuating member 28 is carried therewith until the bell crank 27 strikes the inner end of the depressed key. This moves the latch member 24 to disconnect the actuating member 28 from the segment 29 and to hold the actuating member in its adjusted position as is well known in the art.

When the segment 29 is returned to the position shown in Fig. 1, a surface 30 thereon, engages a pin 31 carried by the actuating member 28 and returns this member to zero. Before this is accomplished the selected totalizers 26 are rocked into engagement with the actuating member so that when this

member is returned to zero the value represented by the depressed key will be entered thereon.

Pivoted to the actuating member 28 is a beam 32 which is bifurcated to cooperate with a stud 33 carried by a link 34. By means of this beam 32 the differential movement of the actuating member 28 is transferred to the link 34 in a manner fully described in the above referred to patents.

At its lower end the link 34 is pivoted to an arm 35 loose on a rod 36 and fast on a spiral segment 37 also carried by said rod.

The segment meshes with a spiral pinion 38 fast on a shaft 39 supported by laterally spaced frames. Also fast on the shaft 39 is a segment 40 which meshes with a rack 41 (Fig. 7). This rack also meshes with a pinion 42 fast on the inner end of a sleeve 43 which at its outer end carries a similar pinion 44 meshing with a type wheel 45. It can be seen from the above that the movement of the differential actuating member 28 will, through the train of mechanism just described, move its appropriate type wheel a corresponding extent.

There are two groups of indicators 55 (Fig. 1) for each of the amount banks of keys 25. One group of indicators indicates toward the front of the machine and the other group indicates toward the back of the machine. There are other groups of indicators which are associated with the various control banks of keys, but as all of these indicators are mounted in a similar manner the group associated with one amount bank only is illustrated and described herein. The group of indicators 55 (Fig. 2) which indicate toward the front of the machine are carried in a casing 56 and rest upon a ledge 57 of a plate 58 slidably mounted on rollers 59 on rods 60 supported by two plates 61, only one of which is shown. The plates 61 are secured to the side frames of the machine by studs 62. The plate 58 has teeth 63 meshing with a segment 64 integral with a segment 65 fast on one of a plurality of sleeves 66 supported by a shaft 67. The upper end of the link 34 is pivoted to the segment 65 so that the differential movement of the differential actuating member 28 is transmitted by means of beam 32 and link 34 to the segment 65 and thereby to the segment 64 and plate 58. In this manner the plate 58 carrying the group of indicators for indicating toward the front of the machine is differentially positioned to bring any desired indicator into operative relation with an indicator-lifting means to be hereinafter described.

The indicators 55 which indicate toward the back of the machine are differentially positioned by means of a plate similar to plate 58. As the indication from the back of the machine is the reverse of that look-

ing from the front, each of the segments 65 is secured to a sleeve 66 so that the movement imparted to the segment 65 is through the sleeve 66 imparted to the plate 58 which carries the indicators 55 for indicating toward the back of the machine. The front and back indicators for the middle amount bank are carried in casings 56 supported by plates 58 integrally connected as shown in Fig. 1.

75

Lifting mechanism.

After the indicators 55 have been differentially positioned according to the keys which have been depressed, the selected indicator is exposed to view. This mechanism is substantially the same as that shown and described in the patent to Fuller No. 1,163,748 granted Dec. 14, 1915. Before the indicators 55 can be differentially positioned it is necessary to lower those exposed during the previous operation. A frame 70 (Fig. 2), rectangular in shape, has at each end an arm 71 carrying a roller 72 projecting into a slot 73 in each plate 61. The frame 70 also has projections 74 at the front and back thereof adapted to engage the indicators 55 in a manner fully described and illustrated in said patent. Pivoted on a stud 75 on the frame 70 is a link 76 also pivoted to a lever 77 fast on a shaft 78 mounted in the side frames of the machine. There is a link 76 and a lever 77 at each end of the machine in order that the frame 70 may be lifted evenly to prevent binding. Pivoted on a stud 79 on the lever 77 is a link 80 which carries a roller 81 projecting into the short portion of an L-shaped slot 82 in a lever 83 loose on a rod 84 carried by the side frames of the machine. The lever 83 has two rollers 85 and 86 cooperating with cams 87 and 88 respectively, fast on the shaft 46. The link 80 has a roller 89 against which rests an edge 90 of a pawl 91 loose on a rod 92 carried by the side frames. A spring 93 holds the pawl 91 against the roller 89 so that the roller 81 is normally maintained in the short portion of the L-shaped slot 82.

From the above description it can be clearly seen that when the cams 87 and 88 are rotated counter-clockwise the lever 83 is rocked clockwise, thereby moving the link 80 downward in the direction of its length and rocking the levers 77 and shaft 78. This movement of the levers 77 through the links 76 lowers the frame 70 and the indicators 55 which were exposed during the preceding operation. As the link 80 is being lowered, the spring 93 maintains the tension against the roller 89 so that the roller 81 cannot become disengaged from the short portion of the slot 82. A stud 94 limits the clockwise movement of the pawl 91.

After the previously exposed indicators 55 have been lowered, as just described, and

115
120
125
130

after the plates 58 have been differentially positioned to select a new indicator, the cams 87 and 88 rock the lever 83 counter-clockwise to home position. This raises the link 80 and consequently rocks the lever 77 counter-clockwise to home position, thereby raising the links 76 to raise the frame 70, whereby the projections 74 thereof engage the selected indicators 55 and expose them to view.

10 After the frame is in its lower position it is held locked in this position until the plates 58 have been differentially positioned to select a new indicator. This locking means will now be described. Slidably 15 mounted on the rods 60 is a plate 95 (Fig. 2), having a slot 96 engaged by a pin 97 on a lever 98 fast on a shaft 99 supported by the side frames. Pivoted to the lever 98 is a link 100 (Fig. 4) which is pivoted to a 20 lever 101 (Fig. 5) loose on the stud 84. The lever 101 has rollers 102 and 103 cooperating with cams 104 and 105 respectively fast on the shaft 46. The cams 104 and 105 are so timed that after the frame 70 has been lowered 25 said cams rock the lever 101 clockwise, which, through the link 100, rocks the lever 98 counter-clockwise and moves the plate 95 toward the left, whereupon a projection 106 thereof engages the roller 72 on the arm 71, thereby holding the frame 70 in its lowered 30 position until the indicators 55 have been selected, after which the counter-clockwise movement of the lever 101 to normal position rocks the lever 98 clockwise to disengage 35 the projection 106 from the stud 72 thereby allowing the frame 70 to be raised to expose the selected indicators to view.

Alining mechanism.

40 Each of the segments 65 has alining notches therein with which an alining bar 107 cooperates. This alining bar 107 is integral with parallel arms 108 (Figs. 2 and 4) fast on the shaft 99, as above described. 45 The lever 98 is fast on the shaft 99. Therefore when said lever is rocked counter-clockwise the shaft 99 rocks the arms 108 counter-clockwise and disengages the alining bar 107 from the notch in the segment 65 so that 50 this segment may be differentially positioned under the control of the differential mechanism. When the lever 98 is rocked clockwise to normal position the aliner 107 is again engaged with a notch on the segment 55 65 to hold the segment in proper position until a subsequent operation of the machine. There is also another alining mechanism 60 109 which directly alines the plates 58. This aliner 109 is in the form of an angle iron (Figs. 2, 3 and 4). In alinement with each plate 58 the aliner 109 has a slot 110 and also an alining tooth 111 which cooperates with notches 112 in the plate 58. The aliner 109 is secured at each end to horizontal 65 portions of levers 113 pivoted on studs

114 mounted in the plates 61. Pivoted to the levers 113 are links 115 which are also pivoted to the levers 98. When said levers are rocked counter-clockwise, as previously described, the links 115 rock the levers 113 clockwise and disengage the alining teeth 111 from the notches 112 of the plates 58. The slots 110 of the aliner 109 then act as a guide for the plates 58 to hold them in proper lateral position. After the desired indicators have been selected and before the frame 70 is raised to expose the selected indicators to view, the levers 98 are rocked clockwise to home position, which movement through the links 115 rocks the levers 113 counter-clockwise, whereby the teeth 111 again engage the notches 112 and hold the indicators in proper alinement until the machine is again operated.

Indicator crippling on totalizing operations.

As above mentioned, in total or sub-total printing operations it is desirable to cripple or render ineffective the indicator-lifting mechanism previously described. To accomplish this result an arm 118 is secured on the shaft 117 and is provided with a pin 119 engaging a slot 120 in a link 129. The ends of this link are bifurcated to surround the rod 92 and the shaft 117. The link 129 carries a roller 130 adapted to cooperate with a surface 131 of the previously described link 80.

It is well known in the art that machines of this type are controlled on total and sub-total printing operations by means of a total lever 135 (Fig. 6). Movement of the total lever either up or down, out of its adding position, rocks the shaft 117 clockwise, to lock out the amount keys and certain banks of control keys, and to control the machine for a two cycle operation as well known in the art. This movement is accomplished in the following manner: Integral with the total lever 135 is a plate 136. A pivoted lever 138 carries a roller cooperating with a slot 137 formed in this plate. Also pivoted on the same center as the lever 138 is a member 139 which has a slot formed therein into which projects a roller carried by an arm 140 fast on shaft 117. The lever 138 and member 139 are connected together by a spring 141 and a pin and slot connection. It can be seen from the above that when the total lever is moved out of its adding position, the lever 138 will be rocked counter-clockwise due to the shape of the slot 137. This movement of the lever 138, through the spring 141, rocks the member 139 also counter-clockwise, which will, in turn, rock the arm 140 and shaft 117 clockwise.

Upon this movement of the shaft 117 the arm 118 will be rocked counter-clockwise as seen in Fig. 2. This movement of the arm 118, through the engagement of the pin 119

with the slot 120, moves the link 129 to the left. This positions the roller 130 into cooperative relation with the surface 131 of the link 80.

5 During adding operations it will be remembered that the link 80 is moved downward by the lever 83 at the beginning of the operation to lower the indicators which were exposed during the last previous operation. During the first part of the movement of the shaft 46 (Fig. 2) the lever 83 is rocked clockwise and lowers the link 80, which lowers the previously exposed indicators to their normal positions. As the link 10 80 nears the end of its downward movement during a total or sub-total printing operation the surface 131 engages the roller 130 which has been moved to the left by movement of the total lever, and rocks the link 15 80 clockwise about the stud 79 thereby disengaging the roller 81 from the short portion of the L-shaped slot 82 and positioning it in the end of the long portion of said slot. Then, when the lever 83 is moved 20 counter-clockwise, to home position, it has no effect upon the link 80, and consequently the indicator lifting frame is not raised to expose selected indicators to view. During 25 the second rotation of the shaft 46 the lever 83 is again rocked clockwise, thereby positioning the short portion of the slot 82 opposite the roller 81. The lever 83 is then again rocked counter-clockwise to home position without lifting the link 80. The total 30 35 or sub-total printing operation is now completed with the roller 81 near the bottom of the long portion of the slot 82. During a total or sub-total printing operation, whichever the case may be, the shaft 117 is 40 rocked still farther in a counter-clockwise direction, by mechanism not shown herein but disclosed in the patents referred to. As the lower portion of the slot 120 is concentric with the shaft 117 the link 129 receives no farther movement to the left than that which was given it by the first counter-clockwise movement of the shaft 117 under the direct control of the total lever 135.

When the total lever is again moved to 50 its adding position it rocks the shaft 117 to home position, thereby rocking the arm 118 clockwise, which moves the link 129 to the right to the position shown. As the machine is now operated and the short portion of the slot 82 positioned opposite the roller 81, the spring 93 through the engagement of the surface 90 of the pawl 91 with the roller 89 will rock the link 80 counter-clockwise thereby moving the roller 81 55 into the short portion of the slot 82. With the roller in this position, the counter-clockwise movement of the lever 83 to home position raises the link 80, rocks the arm 77 counter-clockwise and raises the link 76 to

65 expose the selected indicators, for this operation, to view.

While the form of mechanism herein shown and described is admirably adapted to fulfill the objects primarily stated, it is to be understood that it is not intended 70 to confine the invention to the one form of embodiment herein disclosed, for it is susceptible of embodiment in various forms all coming within the scope of the claims which follow. 75

What is claimed is:

1. In a machine of the class described, the combination of a group of indicators, an actuator common to said indicators, means for adjusting the group of indicators from one 80 position to another to establish cooperative relation between the actuator and any desired indicator, means for operating the actuator to expose the indicator desired, and means for rendering said operating means 85 ineffective.

2. In a machine of the class described, the combination of a group of indicators, an actuator common to said indicators, means for adjusting the group of indicators from one 90 position to another to establish cooperative relation between the actuator and any desired indicator, means for operating the actuator to expose the indicator desired, and means operated as a preliminary to an operation 95 of the machine for determining whether said actuator will be operated by said operating means.

3. In a machine of the class described, the combination of a group of indicators, 100 an actuator common to said indicators, means for adjusting the group of indicators from one position to another to establish cooperative relation between the actuator and any desired indicator, means for operating the 105 actuator to expose the indicator desired, and a differentially adjustable member operated as a preliminary to an operation of the machine for determining whether said actuator will be operated by said operating means. 110

4. In a machine of the class described, the combination of a group of indicators, an actuator common to said indicators, means for adjusting the group of indicators from one position to another to establish cooperative 115 relation between the actuator and any desired indicator, means for operating the actuator to expose the indicator desired, a manually operable device adapted to be adjusted to any one of a plurality of positions, and means operated by said device for rendering the operating means ineffective when said device is set in certain positions. 120

5. In a machine of the class described, the combination of a group of indicators, an actuator common to said indicators, means for adjusting the group of indicators from one position to another to establish cooperative 125

- relation between the actuator and any desired indicator, means for operating the actuator to expose the indicator desired, a differentially adjustable member operated 5 as a preliminary to an operation of the machine, and means cooperating with said operating means and operated by said member for rendering said operating means ineffective.
- 10 6. In a machine of the class described, the combination of a group of indicators, an actuator common to said indicators, means for adjusting the group of indicators from one position to another to establish cooperative relation between the actuator and any desired indicator, means for operating the actuator to expose the indicator desired, means for actuating said operating means, and means for disengaging the operating 15 means from said actuating means.
7. In a machine of the class described, the combination of a group of indicators, an actuator common to said indicators, means for adjusting the group of indicators from 20 one position to another to establish cooperative relation between the actuator and any desired indicator, means for operating the actuator to expose the indicator desired, and means operated as a preliminary to an operation 25 of the machine for rendering said operating means ineffective.
8. In a machine of the class described, the combination of a main operating device, a group of indicators, a common actuator 30 therefor, means for adjusting the group of indicators from one position to another to bring any desired indicator into cooperative relation with said actuator, means for operating the actuator to expose the selected 35 indicator, a flexible connection between the last mentioned means and the main operating device, and manipulative means controlling said connection.
9. In a machine of the class described, the combination of a main operating device, a group of indicators, a common actuator 40 therefor, means for adjusting the group of indicators from one position to another to bring any desired indicator into cooperative 45 relation with said actuator, means for operating the actuator to expose the selected indicator, a flexible connection between the last mentioned means and the main operating device, a manipulative device adapted 50 to be moved into any one of a plurality of positions as a preliminary to an operation of the main operating device, and means cooperating 55 with the flexible connection and operated by the manipulative device whereby said connection is moved so that the main operating device has no effect upon said connection thereby preventing the indicator actuator from being operated to expose the 60 indicators to view.
- 65 10. In a machine of the class described, the combination of a main operating device, a group of indicators, a common actuator 65 therefor, means for adjusting the group of indicators from one position to another to bring any desired indicator into cooperative 70 relation with said actuator, means for operating the actuator to expose the selected indicator, a flexible connection between the last mentioned means and the main operating device, and manipulative means operated as a preliminary to an operation of the machine 75 for determining whether said flexible connection will be effective to cause the selected indicator to be exposed to view.
11. In a machine of the class described, the combination of a plurality of indicators arranged in groups, an actuating device therefor adapted to expose any desired ones of said indicators and hold the same in exposed position, means for adjusting any desired ones of said groups to establish cooperative 80 relation between said device and desired ones of said indicators, means for operating said actuating device, and manipulative means operated as a preliminary to an operation of the machine to control the actuating device to return the previously exposed indicators 85 to normal but not to expose the newly selected ones.
12. In a machine of the class described, the combination of a movable frame, a plurality of vertically movable indicators mounted therein, an actuating device common to all of said indicators, means for moving said frame relative to the actuating device to establish a cooperative relation between said device and any desired one of said indicators, means for operating the actuating device to expose and retain in exposed position the indicator cooperating with said device, and a manually operable member operated only as a preliminary to an operation of the machine to render the actuating device ineffective after the previously exposed indicator has been returned to normal position.
13. In a machine of the class described, the combination of a movable frame, a plurality of vertically movable indicators carried thereby, an actuating device common to all of said indicators, means for moving said frame from one adjusted position to another to establish cooperative relation between said device and any desired indicator, means for operating the actuating device to lift the indicator cooperating therewith and hold the same in exposed position, a differentially adjustable member, and means operated by said member and cooperating with said actuating device whereby said device is operated to restore the previously exposed indicator to normal and then disconnected from the operating means whereby the newly selected indicator is not exposed to view.
14. In a machine of the class described, the combination of a main operating mecha-

- nism, a plurality of vertically movable indicators arranged in groups, devices operated by the main operating device for adjusting said groups of indicators to select any desired ones for operation, means driven by the main operating mechanism for elevating the selected indicators and maintaining the same in exposed position, a manually operable member, and a device controlled by said member and cooperating with said elevating means so that the elevating means restores the exposed indicator to normal after which said elevating means is disconnected from the main operating mechanism thereby preventing the newly selected indicator from being exposed.
15. In a machine of the class described, the combination of a main operating mechanism, a plurality of vertically movable indicator slides arranged in groups, connections actuated by the main operating mechanism for adjusting said groups to bring any desired ones of said slides in the same vertical plane, means driven by the main operating mechanism and having a constant movement in the plane of adjustment of the selected slides and adapted to engage and expose the selected slides and maintain the same in position between operations of the main operating mechanism, and a manually operable member operated as a preliminary to an operation of the machine for controlling the said driven means whereby the exposed slide is returned to normal position and said driven means is disconnected from the main operating mechanism to prevent the selected slide from being exposed when said mechanism is operated.
16. In a machine of the class described, the combination of a longitudinally movable frame, a plurality of slides mounted therein bearing indicating characters, an element designed to withdraw any slide from the frame to expose the characters to view, means for moving said frame directly from one position to another to engage a desired slide with the aforesaid element, manipulative devices controlling said means, devices for giving the aforesaid element an invariable movement, a manually operable member, and means operated thereby for preventing the withdrawal of the desired slide by said element.
17. In a machine of the class described, the combination of a longitudinally movable frame, a plurality of vertically movable indicators carried thereby, an element having an invariable vertical movement, means for moving the indicator frame directly from one position to another to bring any desired indicator into co-operative relation with the invariably moved element, means whereby said invariably moved element will positively raise and lower the selected indicator, and means operated as a preliminary to an operation of the machine to prevent said element from raising the selected indicator but allowing said element to lower the previously exposed indicator.
18. In a machine of the class described, the combination of a plurality of indicators slidably mounted in a movable frame, an invariably and positively reciprocated element, means for moving the indicator frame directly from one position to another to bring any desired indicator into cooperative relation with the invariably reciprocated element, said element being arranged to expose positively the positioned indicator and positively restore it to concealed position, a manipulative device, and means controlling said element and operated by said manipulative device whereby said element will not expose the positioned indicator.
19. In a machine of the class described, the combination of a movable frame, a plurality of indicators carried thereby, each indicator having a pair of oppositely extending projections, a vertically reciprocated actuator common to all of the indicators and arranged to engage the projections on an indicator in such a manner that the indicator will be positively raised and lowered as the actuator is reciprocated, means for adjusting the aforesaid movable frame relative to said actuator while the latter is in lowered position to bring the extensions on any desired indicator into engagement with the actuator, and means for maintaining the actuator in its lowered position to prevent it from raising the selected indicators.
20. In a machine of the class described, the combination of a plurality of vertically movable indicator slides arranged in groups, means for adjusting said groups to bring any desired ones of said slides in the same vertical plane, a single means having a constant movement in the plane of adjustment of the selected slides and adapted to engage and move and maintain said selected slides in exposed position, a manually operable device operated as a preliminary to an operation of the machine, and means operated thereby to control said single means whereby said single means releases the previously exposed slide and engages the newly selected slide but does not move the newly engaged and selected slide to exposed position.
21. In a machine of the class described, the combination of a group of indicators, exposing means common to all indicators, means for adjusting the group of indicators to bring any desired one into cooperative relation with said exposing means, and means for rendering said exposing means ineffective.
22. In a machine of the class described, the combination of a group of indicators, an exposing device common thereto, means for adjusting the group of indicators to

bring any desired one into cooperative relation with said exposing device, and means operated as a preliminary to an operation of the machine for preventing an operation 5 of said exposing device.

23. In a machine of the class described, the combination of a group of indicators, an exposing device common thereto, means for adjusting the group of indicators to bring 10 any desired one into cooperative relation with said exposing device, driving means for said exposing device, and means for disconnecting the exposing device from the driving means.
- 15 24. In a machine of the class described, the combination of a plurality of groups of indicators, an exposing device common to the indicators of all groups, means for adjusting the groups of indicators to bring 20 any desired one of each group into cooperative relation with said exposing device, a manipulative device adapted to be moved into any one of a plurality of positions, and means operated by said device for controlling 25 the effectivity of said exposing device.
25. In a machine of the class described, the combination of a plurality of groups of indicators, an exposing device common to the indicators of all groups, means for adjusting 30 the groups of indicators to bring any desired indicator in each group into

cooperative relation with said exposing device, driving means for said exposing device, a manipulative device adapted to be moved into any one of a plurality of positions, and means operated by said device for controlling the effectivity of said driving means. 35

26. In a machine of the class described, the combination of manipulative devices, a totalizer, indicators, means controlled by the manipulative devices and common to the totalizer and the indicators for actuating the totalizer and selecting an indicator, means for exposing the selected indicator to 40 view, total controlling mechanism, means controlled by said mechanism whereby the first mentioned means is controlled by the totalizer to select the indicator, and means for rendering the exposing means ineffective 45 when the indicator is selected by the totalizer.

27. In a machine of the class described, the combination of normally concealed indicators, means for moving the indicators into view, driving means for said moving means, and means for rendering said driving means ineffective with respect to said moving means. 50

In testimony whereof I affix my signature.

BERNIS M. SHIPLEY.
